US0D1074821S

(12) **United States Design Patent** (10) Patent No.: **US D1,074,821 S**
(45) Date of Patent: ** May 13, 2025

(54) **GAMING MACHINE WITH CARD READER**(71) Applicant: **Aristocrat Technologies, Inc.**, Las Vegas, NV (US)(72) Inventors: **Paul Barker**, Chicago, IL (US); **Timothy Barbour**, Nolensville, TN (US); **Frank Rodriguez**, Las Vegas, NV (US); **Xiaoqiang Gong**, Henderson, NV (US); **Rajendrasinh Jadeja**, Las Vegas, NV (US); **Charles Miller, Sr.**, Henderson, NV (US); **Timothy Seckel**, Streamwood, IL (US)(73) Assignee: **Aristocrat Technologies, Inc.**, Las Vegas, NV (US)(**) Term: **15 Years**(21) Appl. No.: **29/830,934**(22) Filed: **Mar. 16, 2022**(51) LOC (15) Cl. **21-03**

(52) U.S. Cl.

USPC ..... **D21/369**(58) **Field of Classification Search**

USPC D21/329, 332, 333, 365, 385, 694, 371, D21/370, 325, 324, 336, 369, 349, 350, D21/397; D20/39, 1, 4, 9, 10, 99; D14/305, 306, 307, 312, 336, 354, 373, D14/172, 129, 401, 126, 439, 432, 450, D14/128, 375, 248, 374

CLAIM

The ornamental design for a gaming machine with card reader, as shown and described.

DESCRIPTION

FIG. 1 is a perspective view of a first embodiment of a gaming machine with card reader showing the new design; FIG. 2 is a front view thereof; FIG. 3 is a rear view thereof; FIG. 4 is a left side view thereof; FIG. 5 is a right side view thereof; FIG. 6 is a top view thereof; FIG. 7 is a bottom view thereof; FIG. 8 an enlarged perspective view thereof; FIG. 9 is a perspective view of a second embodiment of a gaming machine with card reader showing the new design; FIG. 10 is a front view thereof; FIG. 11 is a rear view thereof; FIG. 12 is a left side view thereof;

FIG. 13 is a right side view thereof; FIG. 14 is a top view thereof; FIG. 15 is a bottom view thereof; FIG. 16 an enlarged perspective view thereof; FIG. 17 is a perspective view of a third embodiment of a gaming machine with card reader showing the new design; FIG. 18 is a front view thereof; FIG. 19 is a rear view thereof; FIG. 20 is a left side view thereof; FIG. 21 is a right side view thereof; FIG. 22 is a top view thereof; FIG. 23 is a bottom view thereof; FIG. 24 an enlarged perspective view thereof; FIG. 25 is a perspective view of a fourth embodiment of a gaming machine with card reader showing the new design; FIG. 26 is a front view thereof; FIG. 27 is a rear view thereof; FIG. 28 is a left side view thereof; FIG. 29 is a right side view thereof; FIG. 30 is a top view thereof; FIG. 31 is a bottom view thereof; and, FIG. 32 an enlarged perspective view thereof.

In these drawings, the solid lines illustrate the claimed ornamental design. The broken lines immediately adjacent the shaded areas represent the bounds of the claimed design, whereas all other broken lines are directed to environment and are for illustrative purposes only. The broken lines form no part of the claimed design.
